Primary Examiner — Dana K Weiland*Assistant Examiner* — Jenny lou M Binas(74) Attorney, Agent, or Firm — JCIP Global Inc.(57) CLAIM

The ornamental design for a floor cleaning machine, as shown and described.

DESCRIPTION

FIG. 1 is a perspective view of a floor cleaning machine showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line portions of the floor cleaning machine shown in the drawings form no part of the claimed design.

1 Claim, 6 Drawing Sheets(56)
